RAILWAY SWITCH

John Knight, Chester, Pa.

Application February 11, 1938, Serial No. 190,110

1 Claim. (Cl. 246—434)

This invention relates to railway switches, and has for its main object the provision of a switch possessing the characteristics of safety and certainty in action, dependability in use, and the elimination of failure to operate properly which has been the cause of many derailings and wrecks. The switch is designed to operate without the use of the usual pivot for the frog and thereby avoids the dangers which may result from loosening or wearing of the pivot.

The above and other objects will become apparent in the description below, in which characters of reference refer to like-numbered parts in the accompanying drawing, forming a part 15 hereof.

Referring briefly to the drawing, the figure is a plan view of a railway switch and the mechanism for throwing the same.

Referring in detail to the drawing, the numeral 20 10 represents one rail and the numerals 11 and 11a represents the other rail of a track section, and the numerals 12 and 13 the curved rails of a switch out track section. The former are secured to the ties, not shown, by the usual bolts or 25 spikes 14 placed at spaced apart intervals along the rails.

The rail 11 terminates at the switch in an extension tongue or frog 15, integral with the rail 11, which at its base is concavely rounded 30 on one side at 16 and convexly on the other side 17. The concavely rounded side 16 at the base of the tongue 15 provides a socket, in which the complementarily rounded extremity 18 of the rail 11a normally registers, that is, when the 35 switch is open. At its extremity the tongue 15 is provided with a flat face 19 at an angle to the sides of the tongue. The curved rails 12 and 13 are secured by bolts 21 to plates 19 and 20, respectively, these plates in turn being secured on 40 the ties, not shown, at the switch. The entire curved section 13 shown is rigidly secured by the said bolts to the plate 20, but the section 12 is secured through part of its length only so that its end tongue 23 beyond the point 22 is free to swing 45 and ride on its plate 19.

The rail 11a is rigid on its ties and on the plate 20 up to the point 24, which is secured to the plate 20 by bolts 25, and the rail beyond the point 24, including the tongue 15, is free to swing about the 50 point 24 as a pivot, on the plate 20.

The extremity of the curved rail 13 is also provided with an angular face 26 which is complementary to the face 19 of the tongue 15. The rail 11a is also held rigid by the bolts 25a and 55 spikes 14.

The switch throwing mechanism comprises the crank 28, the shaft 29 rotatably supported in standards 30, and the oppositely disposed U-shaped bends or cranks 31 and 32 formed in the shaft 29. A lever 33 is pivoted at one end to the crank 31 and at the other end to the side of the tongue 23. Likewise, a lever 34 is pivoted at one end to the crank 32 and at the other end to the side of the tongue 15. The manually operated switch throwing mechanism just described is for 10 purposes of illustration only, as any other suitable mechanism, whether manually or mechanically operated, may obviously be used for the purpose of throwing the switch.

With the switching mechanism in the position shown, a train on the rails 10 and 11—11a will pass straight along these rails, as the switch is open. When the crank 28 is thrown so as to cause a train to be switched from the rails 10 and 11 to the curved rails 12 and 13, the cranks 31 and 32 will assume positions directly opposite to those shown, the end of the rail 11 beyond the point 24 will be bent into the position shown in broken lines, and at the same time the tongue 23 will be urged flush against the rail 10. The end of the rail 11 will bend freely about the point 24 as a pivot, and the section 16 will likewise bend freely about the point 22 as a pivot. When the tongue 15 is in the position shown in dotted lines, the end faces 19 and 26 will lie in mutual engagement and the face 26 will serve as a limit stop to the outward swing of the tongue 15.

Obviously, modifications in form and structure may be made without departing from the spirit and scope of the invention.

I claim:

In a railway switch adapted to operate in conjunction with the two rails of a straight ahead track, a pair of curved rails forming part of the switch, one of said straight rails being divided 40 into two sections, one of said sections having a tongue extension thereon overlapping the other of said two sections, said tongue extension being pliable, one of said curved rails extending toward said one straight rail, the other of said curved 45 rails extending toward the other of said straight rails and having its end free and pliable, switch control means connected to said other curved rail and to said tongue extension for simultaneously bending said free end of said other curved 50 rail and said tongue extension in mutually opposite lateral directions from a position in which said free end of said other curved rail lies against said other straight rail and said tongue extension lies clear of said other section of said one straight 55 rail.

5 rail into a position in which said free end of said other curved rail lies clear of said other straight rail and said tongue extension lies against the end of the other section of said one straight rail, and vice versa, said tongue extension being concavely rounded to form a socket at its base, said

end of said other section of said one rail being complementarily rounded to register in said socket when said tongue extension lies in position against said other section of said one rail.

JOHN KNIGHT.
